UNITED STATES PATENT OFFICE.

ARTHUR O. GRANGER, OF PHILADELPHIA, PENNSYLVANIA, ASSIGNOR TO
THE UNITED GAS IMPROVEMENT COMPANY, OF SAME PLACE.

PROCESS OF MANUFACTURING GAS.

SPECIFICATION forming part of Letters Patent No. 334,701, dated January 19, 1886.

Application filed September 29, 1885. Serial No. 178,594. (No model.)

To all whom it may concern:

Be it known that I, ARTHUR O. GRANGER, of the city and county of Philadelphia, and State of Pennsylvania, have invented an Improvement in the Process of Manufacturing Gas, of which the following is a specification.

My invention has reference to processes for the manufacture of gas; and it consists in first passing the products of combustion from a water-gas generator heated by direct internal combustion through one set of flues of a superheater having two sets of flues, heating said superheater, and raising the carbon of a generator to incandescence by said internal combustion, then passing the water-gas produced in said generator by the decomposition of steam through the other set of flues in the superheater; and it further consists in first passing the products of combustion from a water-gas generator heated by direct internal combustion through one set of flues of a superheater having two sets of flues, heating said superheater, and raising the carbon of the generator to incandescence by said internal combustion, then passing the water-gas produced in said generator by the decomposition of steam, after being admixed with a hydrocarbon fluid or vapor, through the other set of flues in the superheater, all of which is fully set forth in the following specification, and shown in the accompanying drawings, which form part thereof.

The nearest approach to my improved process is shown in the Patent to Rew, No. 290,930, of 1883, and Langdon, No. 263,921, of 1882; but these patents are for processes widely differing from mine in the main features. Rew shows an apparatus in which the process of generating water-gas is continuous and in which there is no step for heating up the contents of the generator worked alternately with the generator of water-gas, and, further, all of the products from the generator pass through the same set of flues, which flues are heated externally by gas otherwise produced. Langdon's apparatus is simply to produce a greater quantity of a heating-gas, part of which is used to continuously heat regenerators through which steam is passed and superheated before being fed to the producer. Both these patents, however, are devoid of the alternative process of heating up and generating gas, and in which

the products from the heating process are used to heat a set of flues or chambers by external combustion, and through which flues or chambers the gas generated as the secondary step is caused to pass.

The object of my invention is to cause the products of combustion from a gas-generator to pass around the outside of superheating or fixing flues of fire-brick or other refractory material, whereby they are heated and by which the water-gas, after being carbureted, is fixed or made permanent by being caused to pass through the said externally-heated flues. This method of working enables the illuminating gas to be rendered fixed or permanent with all the effects of the former method of heating the fixing-chamber by internal combustion, and with none of the disadvantages thereto due to clogging or filling up of the passages or flues from the products of combustion when heating up. The walls of the flues being comparatively thin, and the heat on the outside thereof being very intense, the fire-brick becomes heated to incandescence, and, when subsequently the water-gas, after being carbureted, is passed through the said flues, the heat thereof fixes the gas, making it permanent.

In the drawings, Figure 1 is a sectional elevation of a water-gas apparatus embodying my invention, and Fig. 2 is a plan view of the air-distributing nozzle removed from the bottom of the generator.

A is the generator. B is the superheater. The generator may be made in any of the well-known manners, being provided with the grate C and the ash-pit D. Surrounding the ash-pit is placed a circular blast-nozzle E. This nozzle is made in the form of a box, and is provided with a large number of small apertures, e, opening under the grate, and by which air is finely divided and allowed to strike the under surface of the grate with an even distribution, thus causing a more perfect combustion and less liability to mechanical disturbance than when a simple large blast orifice or opening is used.

F is the air-supply pipe, and the blast is controlled by a suitable valve.

G is the steam-nozzle for admitting steam under the grate-bars.

Superheater B is provided with a lower com-

bustion-chamber, K, having an arched roof, J, which roof supports the filling H, consisting, preferably, of vertical tubes or passages opening into the chamber K, through the roof thereof. These fixing-flues H are preferably formed of fire-brick or other refractory material, and the spaces I between them form a heating-flue. The chamber K and the spaces or flues I are connected with the generator by flues N and N', respectively, either one of which may be closed by a valve, O.

L is a hydrocarbon nozzle for admitting fluid hydrocarbon or other carbureting medium to the water-gas prior to its passage through the 15 superheater.

M is a blast-pipe for admitting air to the heating flue or space I.

P is the gas-outlet from the top of the superheater and leads to the washer.

20 R is the chimney-flue, and is provided, as usual, with a suitable valve.

The operation is as follows: A fire being built in the generator, air is admitted by pipe F, and the products of combustion from the 25 coal contained therein are caused to pass through flue N', and are burned in the space or flue around the fixing-flues H, raising them to incandescence and passing off by chimney R. When the superheater is heated and the coal 30 in the generator has been raised to incandescence, the blast from pipe F is shut off, valve R closed, blast from pipe M shut off, steam from pipe G admitted to the bottom of the generator, and hydrocarbon from nozzle L turned 35 on. Now, the water-gas produced in the generator passes through flue N into chamber K, where it mixes with hydrocarbon fluid, either in the liquid or highly-subdivided condition, by spraying or being previously vaporized, 40 and the carbureted water-gas so produced passes up through the flues H, becoming fixed and ultimately pass off by the pipe P of the washer to holder.

While the construction shown is simple, it 45 is evident that the details thereof may be modified in various ways without departing from my invention.

Having now described my invention, what I claim as new, and desire to secure by Letters Patent, is—

1. The herein-described process, which consists in first passing the products of combustion from a water-gas generator heated by direct internal combustion through one set of flues of a superheater having two sets of flues, 55 heating said superheater and raising the carbon of the generator to incandescence by said internal combustion, then passing the water-gas produced in said generator by the decomposition of steam through the other set of flues 60 in the superheater, fixing the gas without bringing it into contact with any deleterious products or deposits from the generator produced when heating up, the said steps of heating up and producing water-gas in the generator being carried on alternately and independently 65 of each other, substantially as and for the purpose specified.

2. The herein-described process, which consists in first passing the products of combustion from a water-gas generator heated by direct internal combustion through one set of flues of a superheater having two sets of flues, 70 heating said superheater and raising the carbon of the generator to incandescence by said internal combustion, then passing the water-gas produced in said generator by the decomposition of steam after being admixed with a hydrocarbon fluid or vapor through the other 75 set of flues in the superheater, fixing the gas without bringing it into contact with any deleterious products or deposits from the generator produced when heating up, the said steps of heating up and producing water-gas in the generator being carried on alternately 80 and independently of each other, substantially 85 as and for the purpose specified.

In testimony of which invention I hereunto set my hand.

ARTHUR O. GRANGER.
